UNITED STATES PATENT OFFICE.

JOHN H. BURKHOLDER, OF ASHLAND, OHIO, ASSIGNOR TO ELITE MANUFACTURING COMPANY, OF ASHLAND, OHIO, A CORPORATION OF OHIO.

LIFT-JACK FOR VEHICLES.

1,119,241.

Specification of Letters Patent.

Patented Dec. 1, 1914.

Application filed October 5, 1912. Serial No. 724,019.

To all whom it may concern:

Be it known that I, JOHN H. BURKHOLDER, citizen of the United States, residing at Ashland, in the county of Ashland and State of Ohio, have invented certain new and useful Improvements in Lift-Jacks for Vehicles, of which the following is a specification.

This invention relates to lift jacks for vehicles, and is an improvement on the style of jack shown and described in Letters Patent of the United States issued to me on the 3rd day of October, A. D. 1912, and numbered 1,004,741, the same being known to the trade as a "tire saver". The said tire saver jack, however, has a certain limitation which it is the object of the present invention to remedy. For example, when the jack is placed beneath a wheel axle or hub and the lift standard is brought up against the same from beneath and engaged a single downward movement of the actuating lever is the limit of action, and the vehicle is thus raised high enough to at least relieve the tire but it cannot be raised higher. Of course this was and is sufficient for tire saving purposes as the jack lifts high enough to take the weight of the load from the wheel and tire, but often it is desirable to raise the vehicle so that the wheel can be rotated or removed, and the present invention provides for this additional elevation and enables the load to be raised step by step to any desired height and also to be lowered by a like movement, all substantially as shown and described and particularly pointed out in the claims.

In the accompanying drawings, Figure 1 is a side elevation of the jack showing the parts in raising position. Fig. 2 is a cross section substantially on line $\alpha-\alpha$, Fig. 1, omitting the upper yoke or pawl. Fig. 3 is an elevation of the jack with the parts in lowering position and the lower pawl engaged, and Fig. 4 is a view corresponding to Fig. 3 with the upper pawl engaged and the lower pawl disengaged, as hereinafter fully described. Fig. 5 is a perspective detail of the tripping or reversing device.

Having reference now to the parts, s represents the standard, which has the usual base and is provided with a plain straight front edge having lateral flanges 2 which are slidably engaged by clips or ears 3 on the ends of the lift-bar or member b . The

said lift bar has an arm a at its top in which the support 4 is rotatably seated through its shank or stem, as formerly, but a rigid support instead of a rotatable one might be used on said arm. The said bar also has the usual ratchet teeth 5 at its front edge, and said teeth are adapted to be operatively engaged by the two yoke or clevis shaped pawls c and d . The upper of these pawls or yokes is pivoted on the short arm or extension 6 on lever 7 inside its pivot 8 at the top of standard s , while the pawl d is pivoted at 9 on said standard and relatively beneath pawl c . The said pawls work in unison as the said bar b is raised and lowered, and the operation of both is step by step on the ratchet teeth 5 . That is only one step is taken at a time with each complete stroke of lever 7 up or down. In either or both directions of movement the pawl or yoke c is positively actuated while the pawl d operates by gravity when the lift-bar is being raised but is released and thrown out to engage the next higher tooth by the reversing mechanism when the said bar is being lowered.

Thus, assuming that the said bar is being raised to lift the load, as in Fig. 1, it will be seen that the pawl d takes and holds the load while pawl c is being lowered to another gripping position, and said pawl d then drops by gravity over the next tooth beneath, being free on its pivot 9 . On the other hand when the load is to be lowered the reversing device h is rotated on its pivot from position Fig. 1 to position Fig. 3. Structurally the said device or part is shown as having controlling arm 10 , an actuating projection or finger 12 and a lug 13 on its inside adapted to engage the pawl d . The said finger is brought into use when the parts are changed to position for lowering the lift-bar, as in Fig. 3, when it is adapted to bear against the swell or enlargement 14 on yoke c and cause the said yoke to swing outward on its pivot and free from engaging relations with the teeth 5 in the lowering operation of the lift-bar, as seen in Fig. 3. Said figure also shows the yoke or pawl d in supporting relations with teeth 5 , and it is free to gravitate to this position the moment that the spring m and arm 10 are pressed back far enough by the action of swell 14 on projection 12 under the weight of the load on the lift-bar and as the lever 7

is being raised. Then as the said pawl drops into action the load is taken from yoke *c* and the counter pressure of spring *m* asserts itself and throws the said yoke out as in Fig. 3. Then as the lift-bar is lowered still farther and the yoke *c* is free it clears itself above finger 12 and drops back to engaging relations and again takes the load on the next tooth above the one it released. 5

10 As it does this the pawl *d* is kicked off by the spring and remains there until it is released by the action of the yoke on projection 12 as before and so on successively. It should be understood here that with the load on the 15 lift-bar the said swell 14 exerts a positive pressure against finger 12 and the spring *m* and forces said parts back while the lift-bar and pawl *c* are being lowered. This liberates pawl *d* from spring pressure and 20 lets it gravitate to engaging position as above described. Said pawl *d* therefore makes such engagement and takes the load on the lift-bar while yoke *c* is lowered a little farther. As this occurs the spring *m* reacts on the device *h* and instantly throws 25 pawl *c* outward clear of teeth 5, Fig. 3. Then instantly said pawl drops back to engaging position, and a reversal of said lever and parts repeats the former operation until 30 at last the load is lowered as far as required. The said spring *m* is secured at about the lower end of the guard or stop 18 which is cast integral with the standard *s* in this instance and has an outwardly extending 35 flange from its bottom upward as shown to afford the spring all the necessary rearward movement and yet serve to prevent the reversing device *h* from being rotated in the wrong direction. These positions severally 40 are seen in Figs. 1, 3 and 4, with slight changes in the position of the spring when the trip *h* is reversed.

It follows from the foregoing that in the raising of the lift-bar the two pawls are 45 free to slide over the backs of the ratchet

teeth and to engage successively as the lift proceeds, first one and then the other and the trip or reversing device *h* is locked back out of use. This is done by rotation of the device to position Fig. 1, thus carrying projection 12 to the rear. On the other hand, when the lift-bar is being lowered the pawl *c* is first kicked off by the action of spring *m* and then the pawl *d* in succession, the throw outward from the ratchet teeth momentarily of each being necessary to obtain the step by step lowering of the lift-bar and load. These movements also are automatic and no hand action is required except to reverse the said trip according to the next movement desired, whether to raise or lower the load. 50 55 60

What I claim is:

1. In lift jacks for vehicles, a standard having a rigid inclined guard extending laterally at its rear and side, a pawl pivoted on said standard in front of said guard, a reversing device on the pivot of said pawl opposite said guard and a flat spring bearing against said device and limited in its 65 outward movement by said guard.

2. In lift jacks, a standard and a lift-bar slidably mounted thereon having ratchet teeth, a lever pivoted on said standard and a yoke hung from said lever engaging said teeth, in combination with a take-up pawl pivoted on said standard relatively beneath said yoke, a reversing device having a finger to engage beneath said yoke and lift the same and a projection on its inner side 75 extending beneath said pawl, a flat spring fixed at its lower end to said standard and adapted to bear against said projection in both its positions of operation.

In testimony whereof I affix my signature in presence of two witnesses.

JOHN H. BURKHOLDER.
